DISPENSING CARTON

George E. Wauda, Neenah, Wis., assignor to
 Marathon Corporation, Rothschild, Wis., a corporation of Wisconsin

Application September 29, 1952, Serial No. 312,081

3 Claims. (Cl. 206—58)

1

This invention relates to a dispensing package or carton for a roll of sheet material for dispensing lengths of such sheet material, and particularly to improved means for opening such a package. These packages are illustrated by the well-known household waxed paper roll package.

Such packages are customarily provided with a serrated metal cutter blade or knife affixed to a free edge of one wall of the carton, against which the sheet material may be pulled to cut free a particular length of the sheet. This blade or knife is frequently at least partially exposed outside the confines of the package, so that in opening the carton to expose the contents for use, there is danger of cutting the fingers or hand on the blade. My invention provides opening means which eliminates this danger of injury.

The construction by which I provide this improvement will be readily apparent from the following description and drawings, wherein:

Figure 1 is a plan view of a paperboard blank for making the dispensing carton,

Figure 2 is a perspective view of the package formed from the blank shown in Figure 1,

Figure 3 is a cross-sectional view taken along the lines 3—3 of Figure 1,

Figure 4 is a perspective view, partially cut away, showing the carton being opened,

Figure 5 is a perspective view, partially cut away, showing the cover of the carton released for opening, and

Figure 6 is a perspective view showing sheet material being withdrawn from a roll of sheet material retained in the package.

Referring first to Figure 1, the carton is made from a single paperboard blank, suitably cut and scored to provide a front wall 10, a bottom wall 11, a rear wall 12, a cover 13 hinged to the rear wall, and a cover flap 14 hinged to the cover. Front wall 10 is provided at each end with end flaps 15. Similarly, bottom wall 11 and rear wall 12 are provided with end flaps 16 and 17, respectively. Dust flaps 17a are hingedly connected to a side edge of flaps 17.

A central portion 18 of cover 13 and cover flap 14 is separately defined, by a perforation line 19 in cover 13 and a cut 20 in cover flap 14. This separately defined portion serves as means to secure the cover in closed position and also as an opening tab, as will be explained later. Hinge line 21, by which cover flap 14 is hingedly connected to cover 13, extends through tab 18 as at 22. A portion of tab 18 lying within cover 13 is cut through by a cut line 23 and is scored along lines 24 and 25. These score lines and the cut

line meet at a common point adjacent hinge line 22, and radiate outwardly to intersect perforation line 19, as best illustrated in Figures 1 and 2. The portion of tab 18 lying within cover flap 14 is provided with a cut score line 26 parallel to hinge line 21. Cut score 26 is cut through the surface of the carton blank which will form the interior of the carton; with cut line 20 it defines a peelable area 30 the function of which will be later described.

The free edge of front wall 10 is provided with a serrated metal cutter blade or knife 27 suitably affixed thereto.

The carton is formed from the blank shown in Figure 1 by folding front and rear walls 10 and 12 perpendicularly to rear wall 11, and then inwardly folding in succession end flaps 16, 15 and 17, the end flaps being thereby overlapped and glued or otherwise adhered together. After the carton is thus set up, a roll 28 of sheet material, such as wax paper, transparent film or metal foil, of suitable dimension to fit in the carton, is positioned in the carton as will be readily apparent from Figures 3, 4 and 5, and the dust flaps 17a are folded over the roll.

After the roll 28 is positioned in the carton, the cover is closed with the cover flap 14 positioned within the carton, interiorly of front wall 10, but with that free portion of tab 18 which is cut from cover flap 14 positioned to extend exteriorly of the carton so as to overlap front wall 10. An adhesive or heat sealable coating 29 is applied to the exteriorly extending portion of tab 18 between cut score 26 and cut line 20, and the tab is then adhered to the exterior of front wall 10. This is best shown in Figures 2 and 3.

The package is thus presented as shown in Figure 2, wherein the metal cutter or knife 27 is exposed and presents an edge which may prove dangerous when opening the carton. It is a purpose of my invention to reduce the probability of an injury from this cause.

When it is desired to dispense lengths of the contained sheet material, the package is opened by grasping the carton from the bottom in one hand and then depressing tab 18 with the thumb of the other hand in the area defined by score lines 24 and 25 and perforation line 19. Since cut line 23 provides an initial line of weakness in this portion of the tab that is being depressed, separation of the tab from cover 13 along perforation line 19 will be initiated at the point of intersection of cut 23 and line 19. This separation will continue outwardly in both directions

along perforation line 19, and as it progresses from the previously mentioned intersection toward each of score lines 24 and 25, the two depressed portions of tab 18 lying respectively between cut 23 and score lines 24 and 25 will tend to hinge downwardly about said score lines. Continued downward pressure of the thumb, coupled with slight outward pull of the thumb normal to front wall 10, will complete the separation of tab 18 from cover 13 along perforation line 19. This procedure is best illustrated in Figures 4 and 5.

As is noted from Figure 5, the cover 13 has been freed to be hingedly opened, without the portion of the hand necessarily adjacent knife 27 during the opening process ever being in danger of contact with the knife. This is because as tab 18 was separated from cover 13, it remained adhered to the front wall 10 and was depressed in the areas previously mentioned to provide a complete protective cover for the thumb over knife 27.

The pressure of the thumb normal to front wall 10 may be continued even after the tab 18 is separated from cover 13. If this is done the tab will also be separated from front wall 10. Since only the area of tab 18 between cut score 26 and cut line 23 has been adhered to front wall 10, this area provides a peelable surface 30 which will readily separate from the rest of the tab to permit the tab to be torn from front wall 10, the peelable surface 30 remaining adhered to front wall 10, as illustrated in Figure 6. It will be apparent from Figure 5 that during the continuance of pressure of the thumb normal to front wall 10 to completely remove tab 18 from the carton, the tab continues to provide a protective cover for the thumb as the tab is drawn outwardly over knife 27.

The cover may then be opened and the sheet material 31 readied for dispensing from the roll 28. This is done by leading the sheet material between the front wall 10 and the cover flap 14, so that it is dispensed adjacent knife 27. At any desired time, the sheet material may then be withdrawn, and pulled downwardly against knife 27 to sever the needed length. This is illustrated in Figure 6. The vacant space or area in cover 13 left by the removal of tab 18 provides a ready access opening for grasping the sheet material for successive dispensings thereof.

The score lines 24 and 25 obviously might be increased in number, or their function performed by equivalent means, without their being any departure from my invention. Likewise, other details shown and described herein might be varied without removing the article thus formed from the scope of my invention. While various details have been above described and illustrated, it is to be understood that my invention is to be limited only as specifically set forth in the following claims.

I claim:

1. Cover retention and opening means for a dispensing carton for the dispensing of a roll of sheet material, said carton including front, bottom, rear and end walls, a cover hingedly connected along one edge to said rear wall, a cover flap hingedly connected to the opposite edge of said cover, and a knife edge connected along the upper free edge of said front wall to permit the severing of desired lengths of said dispensed sheet material, said means comprising a central portion of said cover and of said cover flap defined by a continuous boundary composed

of a perforation line in said cover and a first cut line in said cover flap, said means in the portion lying within the cover having a second cut line therethrough substantially perpendicular to the hinge connection between the cover and the cover flap and extending from adjacent said hinge connection to intersect said perforation line, and a pair of score lines lying one to each side of and at an angle with said second cut line and intersecting said second cut line adjacent said hinge connection between the cover and the cover flap the carton being closed with said cover flap lying interiorly of the front wall and knife edge and adjacent thereto, the portion of said means adjacent the hinge connection between the cover and cover flap overlying said knife edge, the portion of said means defined from said cover flap lying exteriorly of said front wall and adhered thereto, the carton being opened by applying finger pressure on said means adjacent the intersection of said second cut line with said perforation line to progressively separate said means from the cover along said perforation line said score lines providing weakness lines serving as hinges for the orderly downward separation of the means from the cover, said means being severable from the front wall by continued pressure thereon normal to the front wall to cause separation at the adherence connection therebetween, the portion of said means defined from the cover overlying said knife edge during such separation of said means from the cover and severance of said means from the front wall, to protect the finger from injury, whereby the carton may be opened to permit dispensing of the contained sheet material.

2. In a dispensing carton formed from a single paperboard blank, the carton including front, bottom, rear and end walls, a cover hingedly connected along one edge to the rear wall, and a cover flap hingedly connected to the opposite edge of the cover, cover retention and releasing means defined from said cover and cover flap by a continuous boundary comprising a perforation line in said cover and a first cut line in said cover flap, said means being hingedly divided by the hinge connection between said cover and said cover flap, the part of said means defined from said cover having a pair of score lines and a second cut line intersecting said perforation at various points and meeting in a common point adjacent said last-stated hinge connection, said second cut line being substantially perpendicular to said hinge connection and said score lines lying each to one side of said second cut line and at an angle thereto, the carton being closed with the cover flap lying interiorly of the carton adjacent said front wall, the part of said means defined from said cover flap lying exteriorly of the front wall of the carton and adhered to the exterior of said front wall to thereby retain the cover in carton-closed position, the portion of said means adjacent the hinge connection between the cover and cover flap overlying said knife edge, the cover being released from said position by applying finger pressure on said means adjacent the said second cut line to progressively separate said means from the cover along said perforation line, said score lines providing weakness lines serving as hinges for the orderly downward separation of said means from said cover, whereby the carton may be opened to permit dispensing of the contained article.

3. Means for releasably retaining the cover of a paperboard carton in closed position, the carton

including front, rear, bottom and end walls, a cover hingedly connected along one edge to the rear wall, and a cover flap hingedly connected to the opposite edge of the cover, said means comprising a first portion defined from said cover and a second portion defined from said cover flap, said means being defined by a continuous boundary in said cover and cover flap, the boundary in the area of the cover comprising a perforation line and in the area of the cover flap comprising a first cut line, said first portion having a second cut line therein extending at a substantial angle to the hinge connection between the cover and cover flap and intersecting said perforation line, and having further a pair of score lines lying one to each side of and at an angle to said second cut line and intersecting said perforation line, the carton being closed with the second portion of said means lying exteriorly of and adhered to the outer surface of the carton front wall, and with the cover flap absent the second portion of said means lying interiorly of said carton front wall, the carton

being opened by application of localized pressure on said means in the area of said second cut line to progressively sever said perforation line and thereby separate said means from said cover, said score lines providing hinge lines for the orderly downward separation of the means from the cover.
